(57) **CLAIM**

The ornamental design for a combination ceiling fan and light fixture, as shown and described.

DESCRIPTION

FIG. 1 is a top view of the combination ceiling fan and light fixture in accordance with my design;

FIG. 2 is a bottom view of the combination ceiling fan and light fixture in accordance with my design;

FIG. 3 is a side elevation view of the combination ceiling fan and light fixture in accordance with my design;

FIG. 4 is a front elevation view of the combination ceiling fan and light fixture in accordance with my design;

FIG. 5 is a perspective view from below of the combination ceiling fan and light fixture in accordance with my design;

FIG. 6 is an enlarged partial side view of the combination ceiling fan and light fixture in accordance with my design;

FIG. 7 is an enlarged partial perspective view from above of the combination ceiling fan and light fixture in accordance with my design; and,

FIG. 8 is an enlarged partial top view of a single blade of the combination ceiling fan and light fixture in accordance with my design, shown separately for clarity of illustration.

The right and left side elevation views are mirror images of each other.

The front and back elevation views are mirror images of each other.
